UNITED STATES PATENT OFFICE.

JOHN KLENK AND SAMUEL H. HAAS, OF PHILADELPHIA, PENNSYLVANIA.

OAR-LOCK.

SPECIFICATION forming part of Letters Patent No. 325,748, dated September 8, 1885.

Application filed January 20, 1885. (No model.)

To all whom it may concern:

Be it known that we, JOHN KLENK and SAMUEL H. HAAS, citizens of the United States, residing at Philadelphia, in the county 5 of Philadelphia and State of Pennsylvania, have invented a certain new and useful Improvement in Oar-Locks, of which the following is a full, clear, and exact description.

The object of this invention is twofold, 10 mainly to provide an "oar-lock" or a "row-lock," as the device is indifferently termed, for automatically engaging the oar against accidental displacement, and to provide means for preventing the stealing of the rowlocks when 15 the boat is left unguarded.

The invention consists in a rowlock having a two-part arm or fork to receive the oar, one member of which is pivoted to and overhangs the other, and provided with a spring to keep 20 it in position over the entrance to the oar-lock and automatically displaced from such entrance by the dropping of the oar into the rowlock, after which it is by said spring returned to cover the entrance and retain the 25 oar within the rowlock until the said pivoted member is retracted by hand.

The invention also consists in means under lock and key in the rowlock itself for locking in and concealing the fastenings used to secure 30 the rowlock to the gunwale or outrigger of the boat, all as will be hereinafter particularly set forth and claimed.

In the accompanying drawings, illustrating 35 our invention, in the several figures of which like parts are similarly designated, Figure 1 is a perspective view of the rowlock and part of an outrigger or gunwale, to which it is secured. Fig. 2 is a side elevation of the same. Fig. 3 is a vertical section with the pivoted member 40 retracted; Fig. 4, a bottom plan view with the rowlock proper turned at right angles to the gunwale or support; and Fig. 5 is a detail inside front elevation of the device for locking in the bolt for fastening on the oar-lock.

45 *a* is an L-shaped arm or upright having an upturned curved finger, *b*, to the lower end of which is pivoted or hinged by pin *c* a hook, *d*, the shank of which is forked to straddle the finger *b*, and the inner and outer edges of which 50 are in the same planes with the inner and outer faces of the finger, respectively, so as to make

a flush finish when the parts are together. The finger *b*, by engaging a portion or web, *d'*, of the hook connecting its forks, serves to limit the movement of the hook toward the upright member of the arm *a*. This hook is normally held by a spring, *e*, (which latter is fast to the arm *a*, and engages a cross-bar, *f*, on the hook,) in an upright position to nearly span the space between the vertical member of the arm *a* and its finger *b*, which space we call the "entrance" to the row-lock. In order to protect the spring, it may be set in a recess, *h*, in the horizontal member of the arm *a*, and in the illustration given said spring is a flat piece of metal engaging the bar *f*, which connects the lower ends of the fork of the hook *d*. The head of the hook is beveled on its face *g* next the upright member of the arm *a*, and hence when pressure is exerted upon said face, as by an oar brought 60 down upon it transversely to the oar's length in the direction of the arrow, Fig. 2, the hook will move on its pivot *c* away from the arm *a* into the position indicated by full lines in Fig. 3 and allow the oar to descend into the row-lock upon the horizontal member of the arm *a*, and the hook will be immediately returned 65 by its spring *e* to its normal position, (indicated by dotted lines in said figure and by full lines in the other figures,) thereby covering 70 the entrance to the rowlock, so that the oar will have the arm *a* for its fulcrum in pulling and the finger *b* and hook *d* to prevent it from jumping out of the rowlock, the finger *b* serving 75 as the fulcrum for backing water. The oar is released by manually pulling the hook back into the full-line position of Fig. 3. The arm *a* is swiveled to a post or standard, *i*, at its lower end by a foot, *j*, stepped in the base *k* of the standard *i*, and at its upper end by a 80 pin or pintle, *l*, in the standard, engaging an offset, *m*, from said arm. This pintle is shown as a screw; but in practice it will be concealed by plating or solder; or any other form of blind joint may be made between the arm *a* 85 and standard *i*. The base *k* of the standard is made or provided with a screw-threaded shank, *n*, projecting from its lower surface, and also with a slot, *o*, and this slot is arranged within the standard, which is made hollow, and receives a screw-bolt, *p*.

In applying the rowlock to a boat's gun-

wale or outrigger the threaded shank is passed through a hole in the latter, and an angular nut, *q*, tightened up on it. A stout plate, *r*, having a hole corresponding in shape with 5 said nut, is then slipped over the latter, and its other end aligned with the gunwale or outrigger. This plate has also a slot, *s*, in its said other end, and the bolt *p* is then passed through the slot *o*, gunwale or outrigger, and 10 slot *s*, and a nut, *t*, having a squared portion, *t'*, of the width of the slot, but longer than wide, so as not to turn in the slots *s*, is then run on the bolt till it is ready to enter the slot lengthwise, which is its only mode of entrance 15 therein. The screw-bolt is then rotated by its nicked head till the squared portion *t'* of the nut *t* is drawn up into the slot *s* tight against the gunwale or outrigger, which may be represented by the part marked *u*. By this construction it will be seen that neither of the 20 nuts *q* or *t* can be run off, and hence the rowlock cannot be removed till access is had to the screw-bolt, and this we propose to give only to authorized persons. To accomplish this, 25 we make an opening or doorway in the hollow standard *i*, and close it by a door, *v*, provided with a lock, *w*, operable by a key carried only by authorized persons. This door has a 30 lip, *v'*, to engage the inside of the wall of the standard next the upper end of its opening, and the bolt *w'* of the lock engages the standard's wall inside at its lower end when projected or thrown. By retracting the bolt *w'* by the lock-key, so as to clear the wall of the 35 standard next the lower end of its doorway, the door may be removed from the standard, and access thus afforded to the screw-bolt *p*. The door may be hinged to the standard; but we prefer to make a blind door. By thus 40 concealing and protecting the rowlock fastenings their loss by theft and the consequent annoyance to boat-owners will be prevented, and the necessity for removing the rowlocks after use obviated. We may, however, use 45 other fastening means or another kind of standard for the oar-lock.

What we claim is—

1. In a rowlock, the arm *a*, having the upright finger *b*, combined with the spring-hook *d*, having its lower end forked and shaped to 50 conform to the outline of the finger and embracing said finger and pivoted to said arm at the lower end of the finger and overhanging the space between the arm and its finger, substantially as described. 55

2. In a rowlock, the arm *a*, having the upright finger *b*, the hook *d*, having its lower end forked and shaped to conform to the outline of and embrace said finger and pivoted to said arm at the lower end of the finger, 60 with its upper hooked end overhanging the space between the arm and its finger, and a spring, *e*, arranged in a recess in the arm and engaging a cross-bar, *f*, on the hook, combined with a standard to which said arm is 65 swiveled, substantially as described.

3. In a rowlock, the arm *a*, having the upright finger *b*, and the spring-hook *d*, having its lower end forked and shaped to conform to the outline of the finger and embrace it and 70 pivoted to said arm at the lower end of the finger and overhanging the space between the arm and its finger, combined with the standard to which the arm is swiveled, and means to lock said arm to the boat, substantially as 75 described.

4. In a rowlock, the oar-receiving device, combined with a hollow standard having a locked door, and screw-bolts, nuts therefor, and locking devices for such nuts, substantially as described. 80

In testimony whereof we have hereunto set our hands this 19th day of January, A. D. 1885.

JOHN KLENK.
SAMUEL H. HAAS.
